CLAIM

The ornamental design for a winter weather boot, as shown and described.

DESCRIPTION

FIG. 1 is a front elevational view of a first embodiment of a winter weather boot showing our new design;

FIG. 2 is a rear perspective view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a top plan view of a second embodiment of a winter weather boot showing our new design;

FIG. 8 is a front perspective view thereof;

FIG. 9 is a bottom plan view thereof;

FIG. 10 is a rear perspective view thereof;

FIG. 11 is a right side elevational view thereof;

FIG. 12 is a left side elevational view thereof; and,

FIG. 13 is a top, front and left side perspective view thereof.

The inner portion of the boot shown in broken lines forms no part of the claimed design.
